UNITED STATES PATENT OFFICE

2,640,327

DUAL EVAPORATOR REFRIGERATION APPARATUS

Carl F. Alsing, Wilbraham, Mass., assignor to Westinghouse Electric Corporation, East Pittsburgh, Pa., a corporation of Pennsylvania

Application July 30, 1949, Serial No. 107,790

4 Claims. (Cl. 62—4)

1

This invention relates to refrigeration apparatus and more especially to such apparatus comprising two refrigerant evaporators supplied by a common refrigerant liquefying apparatus.

It is an object of the invention to provide a vessel which houses portions of the temperature regulating apparatus of one of two evaporators and also forms a refrigerant header for both evaporators.

It is a further object of the invention to provide a temperature regulating apparatus for each of two evaporators which apparatus also starts the operation of the refrigerant supplying apparatus when either of said evaporators requires liquid refrigerant.

These and other objects are effected by my invention as will be apparent from the following description and claims taken in connection with the accompanying drawings, forming a part of this application, in which:

Fig. 1 is a view in perspective of a refrigerator cabinet adapted for use with the refrigerating apparatus of this invention;

Fig. 2 is a schematic view in perspective of the refrigerating apparatus of this invention;

Fig. 3 is a sectional view of a portion of the temperature regulating device of one of the evaporators shown in Fig. 2;

Fig. 4 is a modification of the refrigerating apparatus of this invention;

Fig. 5 is a view similar to Fig. 3 and shows the temperature regulating apparatus of one of the evaporators of Fig. 4; and

Fig. 6 is a view in elevation of the apparatus shown in Fig. 5.

Referring now to Figs. 1, 2 and 3, of the drawings, the reference numeral 10 designates the food storage chamber of the refrigerator. This chamber 10 is divided by a horizontal partition 12 into an upper compartment 14 maintained at a temperature at about 40° F. and a lower compartment 16 located below the partition 12 and maintained at a temperature of about 0° F.

The lower compartment 16 is cooled by the first portion 18 of a refrigerant tube 20 which is secured to the bottom wall, the two side walls, and top wall of the lower compartment 16. A second portion 22 of the tube 20 extends upwardly and passes downwardly through a vessel 24. The downwardly extending end of the portion 22 is secured to the metal side wall 26 of the upper compartment 14 by a metal clip 28 and the end 30 of the tube portion 22 is closed. The tube portion 22 within the vessel 24 has an opening 32 located near the base of the vessel 24

2

and another opening 34 in an upper portion of the vessel 24.

An inclined tube 36 extends through the bottom of the vessel 24 and the upper end of the tube 36 is located adjacent the opening 34 to receive any refrigerant liquid issuing therefrom. The tube 36, at its lower end, communicates with a somewhat smaller tube 38 which is secured against the upper portion of the metal side walls and rear wall of the upper compartment 14 and forms a refrigerant evaporator to cool this compartment. The upper end 39 of the tube 38 communicates with the upper portion of the vessel 24.

A suction tube 40 communicates with an upper portion of the vessel 24 and with a sealed casing 42 which houses a refrigerant compressor 44 and an electric motor 46 for driving the compressor 44. The refrigerant vapor enters the compressor 44 through an inlet tube 48 and leaves the compressor 44 through a pressure tube 50 which conducts it to an air-cooled condenser 52. The condensed refrigerant liquid flows from the condenser 52 through a capillary tube 54 to the entrance of the tube 20.

The electric motor 46 receives power through leads 56, and a thermostatic switch 58 is interposed in one of the leads 56. A bulb 60 is located in heat-transfer relationship with the first portion 18 of the tube 20 and contains a volatile liquid, the vapor pressure of which is transmitted through a tube 62 to the thermostatic switch 58. The bulb 60 and the thermostatic switch 58 energize the motor 46 when the temperature of the first portion 18 of the tube 20 rises above a predetermined temperature and shuts off the motor 46 when the temperature of this tube portion 18 rises above a second predetermined temperature which is higher than the first predetermined temperature.

40 *Operation of first embodiment*

When in operation, the refrigerant supplying apparatus supplies liquid refrigerant through the capillary tube 54 to the tube 20, and the first portion 18 of the tube 20 is maintained between predetermined temperature limits by the thermostat 58. Sufficient refrigerant liquid is supplied to the tube 20 so that some of it flows into the vessel 24 to the height indicated by the dotted line 64.

45 If the upper food storage compartment 14 is warmer than a certain predetermined temperature, some of the refrigerant liquid in the portion of the tube 20 which extends through the vessel 24 is vaporized by the heat conducted to it by the clip 28 and the tube portion below the opening

34 forms a vapor actuated lift pump which draws in refrigerant liquid through the opening 32 and discharges it through the opening 34. The mixture of refrigerant liquid and vapor issuing from the opening 34 flows into the tube 36 where the refrigerant liquid tends to separate by gravity from the vapor and runs down into the tube 38 to refrigerate the same, whereas the refrigerant vapor is drawn upwardly through the suction tube 40 if the refrigerant supplying apparatus is running.

The column of refrigerant liquid and vapor in the tube portion 22 between the openings 32 and 34 will also oppose the flow of any refrigerant liquid running downwardly in the portion of the tube 22 above the opening 34 so that this downwardly running liquid is diverted through the opening 34 directly into the tube 36. The refrigerant liquid vaporized in the tube 38 returns to the vessel 24 through the upper end 39 of the tube 38. It is thereafter withdrawn through the suction tube 40.

It will be apparent from the above that if the refrigerant apparatus is operating, the lower compartment 16 will be cooled until its lower temperature limit is reached and that refrigerant liquid will also be supplied to tube 38 to refrigerate the upper compartment 14 if its temperature is above a certain predetermined temperature.

Description of second modification

Referring now to Figs. 1, 4, 5 and 6 showing the second modification of the invention, the parts which are identical to those of the first modification are provided with the same reference numerals as those of the first modification. Parts which are merely similar to those of the first modification are provided with the same reference numerals as those of the first modification but with the suffix *a* added thereto.

In the second modification, the capillary tube 54a discharges directly into a larger tube 66 which extends downwardly through the vessel 24a. The tube 66 is provided with openings 32 and 34 through which the refrigerant liquid may flow into the interior of the vessel 24a. The lower end of the tube 66 is closed and is in heat exchange relationship with an electric heater 70 which is supplied with electrical energy through the leads 72 and controlled by a switch 74. The switch 74 is responsive to the pressure of a volatile liquid located in a bulb 76 which pressure is transmitted to the switch 74 through a tube 78.

The upper compartment 14 of the refrigerator is cooled by a tube 38a into which the refrigerant liquid is transferred through the opening 34 in the same manner as in the previous modification. The tube 38a is in heat transfer relationship with the bulb 76. A second bulb 60a is located in heat-transfer relationship with the tube 66. A volatile liquid in the bulb 60a actuates the switch 59 through the tube 62.

A tube 18a communicates at both ends with a lower portion of the vessel 24a and is secured to the walls of the lower compartment 16 in the same manner as the tube 18 of the first modification. The vessel 24a, the tube 66, the heater 70 and the bulb 60a are located in the thermal insulation of the walls of the refrigerator.

Operation of second embodiment

The refrigerating supplying apparatus 42, 52, when actuated, supplies sufficient refrigerant liquid to fill the vessel 24a as well as the tube 18a.

If the temperature of the tube 38a, which cools the upper or warmer compartment, exceeds a predetermined value, the switch 74 closes and energizes the heater 70. This vaporizes the refrigerant liquid in the tube 66 and the action of the vapor actuated lift pump comprising the tube 66 commences. Refrigerant liquid is forced through the opening 34 and flows into the tubes 36 and 38a.

At the same time the heater 70 warms the bulb 60a to close the switch 59 if open and actuate the refrigerant supplying apparatus, 42, 52. Refrigerant liquid is thereupon supplied to the vessel 24a and the vapor pressure in the vessel 24a is reduced. This vaporizes the refrigerant liquid in the tube 38a and cools the upper compartment 14 of the refrigerator.

When tube 38a is cooled to the predetermined temperature at which switch 74 opens, the heater 70 is deenergized and the pumping action of the tube 66 ceases. The refrigerant supplying apparatus 42, 52 continues to operate until tube 66 is reduced to the temperature at which switch 59 opens. Before tube 66 reaches this temperature, however, all of the refrigerant liquid in tube 38a evaporates since it now is the warmest refrigerant liquid on the suction side of the refrigerant supplying apparatus 42, 52.

When the refrigerant liquid in the evaporator 38a has evaporated, tube 66 will assume the same temperature as the tube 18a since tube 66 is located in the thermal insulation of the cabinet and is subjected to the same suction pressure as the tube 18a. Tube 66 together with tube 18a is now cooled until the bulb 60a opens the switch 59.

Tubes 66 and 18a tend to be at the same temperature even when the refrigerating apparatus 42, 52 is inactive because both are subjected to the same pressure. If tubes 66 and 18a warm up to the temperature at which switch 59 closes before the tube 38a warms up to the temperature at which switch 74 closes, the refrigerant supplying apparatus 42, 52 will be energized but will supply only the tubes 18a and 66.

While in this modification the refrigerant liquid is conducted directly to the vessel 24a, this is not essential since it might also be conducted directly to the tube 18a as in the first modification of the invention. It will be apparent from the above that in each of the modifications, the vessel 24 and 24a forms a refrigerant header for both the tubes which cool the upper compartment and the lower compartment as well as for the vapor actuated lift pump. It will be further apparent that in the second modification, the refrigerating apparatus will be actuated when either the upper compartment or the lower compartment of the refrigerator requires refrigeration and the compartment requiring refrigeration will be cooled substantially to the exclusion of the other compartment.

While I have shown the invention in several forms, it will be obvious to those skilled in the art that it is not so limited, but is susceptible of various changes and modifications without departing from the spirit thereof.

What I claim is:

1. In refrigerating apparatus, the combination of a vessel adapted and arranged to store refrigerant liquid, refrigerant vapor compressing and condensing apparatus adapted to supply refrigerant liquid to said vessel, a first evaporator, a first conduit connected at one end to said vessel at a first portion thereof spaced from the bottom of the vessel, said first conduit being connected at

its other end to said first evaporator, said first conduit conducting refrigerant liquid from said vessel to said first evaporator, a second evaporator, a second conduit connected at one end to said vessel at a second portion thereof located at an elevation above that of said first portion, said second conduit being connected at its other end to said second evaporator, and a pump adapted to pump refrigerant liquid from an area of said vessel located below said first portion, said pump discharging said liquid into said second conduit.

2. The refrigerating apparatus defined in claim 1 including means for actuating said pump in response to a predetermined high temperature of said second evaporator.

3. The refrigerating apparatus defined in claim 1 including temperature-responsive means for controlling said compressing and condensing apparatus to maintain the temperature of said first evaporator substantially constant and to actuate said pump in response to the temperature of said second evaporator to keep the temperature of the latter substantially constant.

4. In refrigerating apparatus, the combination of a vessel adapted and arranged to store refrigerant liquid, refrigerant vapor compressing and condensing apparatus adapted to supply refrigerant liquid to said vessel and withdraw refrigerant vapor therefrom, a first evaporator, a first conduit means connected at one end to said vessel at a first portion thereof spaced from the bottom of the vessel, said conduit means being adapted and arranged to conduct refrigerant

liquid from said vessel to said first evaporator and refrigerant vapor from said first evaporator to said vessel, a second evaporator, second conduit means connected at one end to said vessel at a second portion thereof, said second portion being at a higher elevation than said first portion, said second conduit means being adapted to conduct refrigerant liquid from said vessel to said second evaporator and refrigerant vapor from said second evaporator to said vessel, a vapor actuated lift pump adapted to pump refrigerant liquid from a portion of said vessel below said first area into said second conduit means, a heater for operating said pump, a first control means responsive to the temperature of said evaporator for actuating said pump when the temperature of said second evaporator rises above a predetermined value, and a second control means responsive to the temperature of the refrigerant liquid in said pump, said second control means being adapted and arranged to actuate said refrigerant vapor compressing and condensing apparatus when the temperature of the refrigerant liquid in said pump exceeds a predetermined value.

CARL F. ALSING.
